UNITED STATES PATENT OFFICE.

CARL J. HAZELTON, OF WORCESTER, MASSACHUSETTS, ASSIGNOR TO AMERICAN NARROW FABRIC COMPANY, OF WORCESTER, MASSACHUSETTS, A CORPORATION OF MASSACHUSETTS.

GARMENT SUPPORTER.

Application filed October 2, 1923. Serial No. 666,074.

To all whom it may concern:

Be it known that I, CARL J. HAZELTON, a citizen of the United States, and a resident of the city of Worcester, in the county 5 of Worcester and State of Massachusetts, have invented certain new and useful Improvements in Garment Supporters, of which the following is a specification.

My invention is directed to an improvement 10 in garment supporters, particularly hose supporters, and one of the objects thereof is the provision of an improved form of button or stud to be employed in connection with such articles.

Another object of my invention is the provision of an improved form of shank for 15 the stud or button, my improved shank facilitating the manufacture of the supporter and eliminating certain more or less 20 objectionable characteristics inherent in garment supporters as now constructed.

Other and further objects of my invention will be apparent from the following description and from the accompanying drawings. 25

Before proceeding with a detailed description of my improved garment supporter, I will refer more or less generally to garment supporters as now constructed so that the 30 improvements of the present application may be fully appreciated.

I am aware that prior to this application garment supporters have been constructed in which the button or stud is provided with an 35 elongated shank having straight faces or surfaces at the sides, the head of the button overhanging the straight sides of the shank. Such a construction, however, possesses certain inherent objectionable characteristics, in 40 that the side flanges alone are relied upon for preventing the holding loop from slipping off the button entirely. In my improved structure, however, the head provides a flange not only at the sides of the stud, but 45 at the front as well.

In manufacturing garment supporters, ease of assembly of the base-plate and button is a desideratum. To this end, therefore, in my improved button I have provided 50 both the front and the back of the shank with a flat face or surface, so that when assembling the parts the button may be readily applied to the base-plate. This construction is of advantage as compared to a button of 55 the type, for example, shown in my co-pend-

ing application, Serial No. 646,614, filed June 20, 1923—wherein I have provided a segmental shank. In that particular form of construction there is only one way of assembling the button and base-plate, so far 60 as the straight front surface is concerned, whereas in the construction employed in the present application the assembler has the choice of two ways. This results in an appreciable saving of time in the assembling 65 operation.

While I have so far discussed but one form of my invention, it is to be understood that the same may take other forms. For instance, the shank of the button may be rectangular so as to have four flat surfaces, thereby preventing turning of the holding loop relatively to the button or vice versa, and also greatly facilitating assembly, particularly if the shank be made square in 75 cross-section.

In all cases I purpose securing the button or stud to the base-plate by securing means, the head of which extends beyond the shank to provide a structure wherein this head will 80 extend beyond the side arms of the holding loop. This feature per se, however, is covered by my co-pending application above referred to, and for this reason will be claimed in the present application only in 85 combination with certain other details of construction with which this feature cooperates, all of which will appear herein-after.

In the accompanying drawings— 90
Figure 1 is a plan view of a garment supporter embodying my improved structure;

Fig. 2 is a section taken on the line 2—2 of Fig. 1, looking in the direction of the arrows;

Fig. 3 is a section on the line 3—3 of Fig. 2, in the direction of the arrows;

Fig. 4 is a plan view of a modified form of construction;

Fig. 5 is a section through the shank of 100 Fig. 4, and

Fig. 6 is a plan view of a still further modified form of construction.

Referring to the drawings in detail, 1 105 designates a supporting member, which is usually of elastic and attached to a metal loop 2. Pivotedly attached to this loop is a supporter-holding loop 3 provided with substantially straight side arms 4 and a straight transverse bar 5, the holding loop 3 being 110

enlarged somewhat adjacent the top thereof, as viewed in Fig. 1, to provide an opening 6 for receiving the head of the supporter button, as will be hereinafter pointed out. 7 5 designates a tab of fabric or of similar material which is attached to the members 2 and 3 and which carries at a lower end, as viewed in Fig. 1, a metal base-plate 8—best seen in Fig. 3. Secured to the base-plate 8 10 is a supporter button or stud 9. This stud is of rubber or similar material and comprises a head 10, which has been shown as oval in plan but which may be round or of other convenient shape, if desired. The stud 15 is provided with a polygonal shank 11, the shank of Fig. 3 being rectangular in cross-section. In other words, the front 12, back 13 and the two opposed sides 14 and 15 are flat or straight. The stud is held in place on 20 the base-plate 8 by means of a rivet 16, the head 17 of this rivet, as will be apparent from Figs. 1 and 2, being elongated so that when the stud is in place on the base-plate—in fact, when the whole supporter is assembled, the head of the rivet will overlie the side arms 4 of the holding loop. The rivet head lies in a groove 18 in the head of the button so as to be slightly depressed below the top surface of the button, as viewed in 30 Fig. 2. I may here mention that the groove 18 co-operates with the elongated head of the stud to assist in preventing turning of the stud on the rivet. The stud is provided further with a flat shank 19, which passes 35 entirely through the stud and through the base-plate 8 on the back of which it is riveted over, as indicated at 20, thereby securing or attaching the button or stud to the base-plate.

40 As previously pointed out herein, it is a desideratum in articles of this character to simplify the structure of the article as much as possible to facilitate assembling. It will be seen from the foregoing description that 45 in assembling the button or stud and the base-plate, the button may be applied to the base-plate as shown or may be given a turn of 180 degrees, inasmuch as the back and front of the stud are alike. In other words, 50 care need not be exercised in assembling the button and base-plate in order to have the front of the stud present a flat surface, as is necessary, for example, in my co-pending application, Serial No. 646,614, and, furthermore, it is unnecessary to exercise particular 55 care in applying the base-plate and its attached stud or button to the tab 7.

60 The head 10 of the button or stud is considerably enlarged with respect to the periphery of the button shank to provide an overhang or flange 21 extending beyond the shank throughout the periphery of the shank, and by extending the head 17 of the holding rivet or beyond the side arms 4 of 65 the holding loop, this overhang or flange

may be said to be reinforced, this construction very effectively preventing accidental removal or dislodgement of the button from the base-plate.

The straight sides 14 and 15 on the shank 70 of the button and the straight faces or surfaces 12 and 13 effectively prevent turning of the button in the holding loop. This is of importance in actual practice, not only insuring that the button will always be in 75 proper position relatively to the holding loop, but also providing a structure in which the garment is held more securely than otherwise possible. I might add that in the case of a button having an oval head, such as illustrated in the drawings of this application, it is desirable that the button be held transversely of the holding loop at all 80 times.

While the shank 11 of the button 9 has 85 been shown as square in cross-section, as seen in Fig. 3, it is to be understood that the shank may be rectangular without being square, the desideratum being a stud provided with a shank which shall have 90 straight sides and a straight front and a straight back.

In the form of my invention illustrated 95 in Figs. 4 and 5, I have provided a base-plate 22, to which is secured a button or stud comprising a head 23 and a shank 24, this button or stud being secured to the base-plate in a manner similar to the button or stud of Fig. 2 by a holding rivet 25. The button of this form of my invention is provided with a straight front 26, straight back 27 and opposed curved sides 28. In this 100 form of my improved device, the front and back of the shank of the stud are straight 105 or flat so as to facilitate assembling of the button and base-plate. In this instance also the head of the button overhangs the shank throughout to provide a flange for co-operation 110 with the side arms and straight transverse bar of the holding loop. The curved sides 28 of the shank of this stud will insure 115 that the button will swing into proper position relatively to the holding loop should these two members, when the supporter is applied to a garment, be improperly positioned relatively to each other.

120 It will be seen from the foregoing that in the embodiment of my invention last described, I have provided a garment supporter structure wherein the front and back of the shank of the stud or button are alike, each being straight or flat, thereby providing a flat surface or face for co-operation 125 with the transverse bar of the holding loop, whether the stud or button is applied to the base-plate as shown in the drawings or turned at an angle of 180 degrees. It will be seen also that not only are the front and back faces of the shank of the button flat or straight, but the front and back of the 130

entire button are alike, so that no particular care need be exercised in attaching the button to the base-plate or the base-plate to the tab 7, as is necessary in garment supporters 5 of prior constructions.

In the form of my invention illustrated in Fig. 6, I have provided a base-plate 29 which is attached to a tab 30 which is similar to the tab 7 of Fig. 1. Mounted on this 10 base-plate is a button or stud comprising a head 31, which may be oval, as illustrated, or of any other shape desired, and a shank 32. The shank, as plainly indicated in the drawings, is flat or straight at the sides, as 15 indicated at 33, and curved front and back, as indicated at 34 and 35, respectively. The head of the button, whatever the shape may be, is large enough at all times to project beyond the shank to provide an overhang 20 or flange all around the shank of the button to prevent the holding loop 36 from slipping off the button entirely. The loop 36 is provided with substantially straight, parallel side arms 37 and a curved cross-bar 25 38, the curvature of the cross-bar substantially conforming to the curve of the front 34 and back 35 of the shank of the button. The head of the button is provided with a groove 39 which receives the head of a stud 40, this stud or holding device passing 30 entirely through the button and through the base-plate in a manner similar to that illustrated in Fig. 2 to thereby securely hold 35 the button in place on the base-plate.

It will be seen that in this form of my invention the button is reversible,—that is to say, the front and back of the shank of the button being curved, the button can be 40 assembled on the base-plate as illustrated, or may be turned at an angle of 180 degrees—in both cases the straight sides and curved front being available for co-operation with the straight side arms and curved 45 cross-bar of the holding loop. As pointed out in connection with the other forms of my improved construction above described, this last construction facilitates assembling of not only the button and base-plate, but 50 the base-plate and holding tab as well—which, in this type of article, is very desirable. By having the head of the button extend beyond the periphery of the shank, I provide a flange under which the holding 55 loop is retained when the article is in use, and by having the head of the stud or rivet, or other holding device, extend beyond the side arms 37 of the holding loop, as illustrated, the head of the button is reinforced 60 and the button retained in place on the base-plate more securely than otherwise possible. I might mention also that this construction will prolong the life of the button as a whole very materially.

65 When employing the square shank of Fig.

3, the button—if an oval button be employed—can even be applied to the base-plate at an angle of 90 degrees to that shown in the drawings without sacrificing any of the holding qualities of the supporter, inasmuch as the flange provided by the head of the button projects beyond the shank throughout so that, even if the button be turned at an angle of 90 degrees when applied to the base-plate, it will still present 70 straight sides and a straight front and will be provided with an overhang or flange under which the holding loop is caught or held.

In the case of the form of the invention shown in Figs. 4 and 5 should the loop and button be improperly positioned initially when the device is applied to a garment to be supported, the curved sides will permit the loop or the button, as the case may be, to swing into proper position automatically. 80 The novel feature of this form of my invention is the formation of the flat or straight front and back faces on the shank of the stud, making it unnecessary to exercise any particular care in assembling the 85 button and base-plate and in assembling the base-plate and its supporting tab.

While I have described specific forms of construction, it is to be understood that changes may be made therein without departing from the spirit and scope of my invention.

What I claim is:

1. In combination a holding loop having side arms and a crossbar, a button adapted to co-operate with said holding loop, said button comprising a head and a shank, said shank having opposed curved faces adapted to co-operate with the side arms of the loop and having two opposed straight faces either of which is adapted to co-operate with said cross-bar, said head overhanging the shank throughout the periphery of the shank to provide a flange to overlie the side arms and crossbar of the holding loop when the loop 100 is in operative position relatively to the button.

2. In combination a base-plate, a button supported thereby, said button comprising a head and a shank, the periphery of said shank being provided with two opposed curved faces or surfaces and with two opposed flat faces, the head of the button overhanging the shank to provide a peripheral flange throughout the periphery of the button, and securing means passing through said button and into said base-plate for securing the button to the base-plate, the head of said securing means projecting beyond 115 the periphery of the shank.

3. In combination a base-plate, a button supported thereby, said button being provided with a shank and an enlarged head, said shank having straight or flat surfaces 120 front and back, and securing means passing 125 front and back, and securing means passing 130

through the head and shank of the button and into said base-plate for attaching or securing the button to the base-plate, said securing means being provided with a head extending beyond the sides of the shank.

4. In combination a base-plate, a button provided with a shank and a head, the shank of the button being provided front and back with flat faces or surfaces, and at the sides **10** with curved faces or surfaces, the head of

said button overhanging the straight and curved surfaces of the shank, and securing means for attaching the button to said base-plate and provided with a head projecting beyond the curved side faces or surfaces of **15** the shank.

This specification signed this 28th day of September, 1923.

CARL J. HAZELTON.
